UNITED STATES PATENT OFFICE.

ALEXANDER K. SUTHERLAND, OF MILWAUKEE, WISCONSIN, ASSIGNOR TO MOE-BRIDGES COMPANY, OF MILWAUKEE, WISCONSIN, A CORPORATION OF WISCONSIN.

DESIGN FOR A LIGHTING FIXTURE.

Application filed November 12, 1924. Serial No. 11,359. Term of patent $3\frac{1}{2}$ years.

To all whom it may concern:

Be it known that I, ALEXANDER K. SUTHERLAND, a subject of the King of England, residing in Milwaukee, in the county of Milwaukee and State of Wisconsin, have invented a new, original, and ornamental Design for Lighting Fixtures, of which the following is a specification, reference being had to the accompanying drawing, forming part thereof.

The figure is a view of a lighting fixture showing my new design.

I claim:

The ornamental design for a lighting fixture as shown.

ALEXANDER K. SUTHERLAND.
